UNITED STATES PATENT OFFICE

LAWRENCE L. NEEBE, OF WOODBURY, NEW JERSEY

CROSTIE FOR LOCOMOTIVES

Application filed August 5, 1931. Serial No. 555,286.

This invention relates to certain improvements in the cross-ties supporting the ball joint of the flexible steam pipe leading from the rear fixed cylinder to the forward cylinder saddle located on the front flexible frame of an articulated locomotive.

The object of my invention is to form an interior passage in the cross-tie which connects the forward and rear sections of the pipe and in which is contained the ball-and-socket joint for the rear section of the pipe.

This invention is particularly adapted to a locomotive of the articulated type in which the front cylinder is fixed to the flexible front frame of the locomotive and the rear cylinder is fixed to the rear frame of the locomotive, and the rear section of the pipe is connected to the rear cylinder structure by a ball-and-socket joint, and, in this case, to the cross-tie by a ball-and-socket joint which is contained within the cross-tie, the forward section of the pipe being rigidly secured to the cross-tie, and both pipes communicating with the interior steam passage of the cross-tie.

In the accompanying drawing:

Fig. 1 is a sectional view through the cross-tie;

Fig. 2 is a plan view; and

Fig. 3 is an end view of the cross-tie.

The invention is an improvement on the construction illustrated in the patent granted to J. C. Maris, No. 1,758,845, granted May 13, 1930. In the patent the cross-tie simply supports the ball section, which was made separate from the cross-tie, the cross-tie being located below the ball-and-socket coupling.

In the drawing the cross-tie 1 is made as a single casting and has flanges 2—2 which are bolted to the side frames 3 of the front section of the locomotive. The cross-tie has pads 19, which rest upon the upper edges of the frames 3, as clearly shown by dotted lines in Fig. 3. An interior steam passage 4 extends from one end of the cross-tie to the other, and this steam passage is preferably tapered at the forward end as shown at 4a, and is connected to a flange 6 of the forward section 5 of the steam pipe, shown

by dotted lines. The flange 6 is tapered to fit the tapered end of the cross-tie so as to make a steam-tight joint, as it will be understood that the section 5 of the steam pipe is rigidly secured to the cross-tie at its rear end and can slide longitudinally in the slip joint 7 of the forward cylinder structure, shown by dotted lines, and in the patent referred to above. The rear end of the passage 4 is enlarged as at 4b, and located in this enlarged portion is the socket 8, in which is a ball 9, shown by dotted lines in Fig. 1, the socket being held in position by a ring 10 or other suitable fastening. The ball is attached to the rear section 11 of the steam pipe, which extends to the rear cylinder structure where it is provided with a ball-and-socket joint as indicated in the above-mentioned patent, so that the steam flowing through the section 11 of the steam pipe passes into the steam passage 4 and from the steam passage 4 into the forward section 5 of the pipe.

Forming an integral part of the cross-tie are arms 12 for the centering spring push rod or valve motion bearings and in the present instance at the forward end of the cross-tie is a bracket 13 for the brake cylinder.

14 are the perforated lugs for the spring links, and 15 are the bearings for the brake 80 hangers. 16 and 17 are webs on which are formed the flanges 2, which are connected to the side frames of the locomotive. Transverse ribs 18 at the top of the structure extend from one side of the cross-frame to the other to support the waist bearer saddle. These ribs also strengthen the arms for the centering spring push rod or valve motion bearings.

It will be seen by the above construction that a very rigid cross-tie can be made in which is an interior steam passage which is connected at one end to the rigid section 5 of the steam pipe and at the other end to the flexible section 11 of said steam pipe, and the socket for the ball joint can be rigidly held in the opening in the enlarged portion of the interior steam passage, making a very substantial construction yet allowing the necessary flexibility of the section 11 of the steam pipe.

It will be understood that, while I have shown one type of ball joint, other types may be used and in some instances the rear end of the cross-tie may have a rigid flange connection instead of the flexible connection for the steam pipe without departing from the essential features of the invention. The cross-tie may have additional arms or brackets as may best suit the design of the locomotive.

10 I claim:

1. The combination of side members of the frame of a locomotive; and a cross-tie connecting the frames, said cross-tie having a longitudinal interior steam passage therein, said passage being enlarged at one end to receive the ball-and-socket connection of the pipe leading from the rear cylinder to the cross-tie and reduced at the other end where the cross-tie is rigidly secured to the section of the pipe leading from the cross-tie to the forward cylinder.
2. A cross-tie for a locomotive made in a single casting and having an interior steam passage therein, and having side flanges by which the cross-tie is secured to the side members of the frames of the locomotive, and having webs at each end connecting the body of the structure to the said flanges.
3. A locomotive cross-tie made in a single casting and having an interior steam passage therein, and having flanges by which it is secured to the side members of the frame of the locomotive, and having lateral arms for supporting accessories of the locomotive.
4. A cross-tie made in a single casting and having an interior steam passage therein and having flanges by which it is secured to the side members of the frame of the locomotive, and having at its forward end a bracket for a brake cylinder.
5. A cross-tie for a locomotive, made in a single casting and having an interior steam passage therein, and having perforated lugs at the upper portion thereof for spring links.
6. A cross-tie made in a single casting, having an interior steam passage therein and having lateral arms for centering spring push rod, and having brake hanger bearings depending from said arms.
7. A locomotive cross-tie made in a single casting, having an interior steam passage therein and having lateral arms for supporting accessories of the locomotive and also having a support for the waist bearer saddle.
